UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,985, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures hereinafter more fully described.

The accompanying photograph illustrates a face view of wall-paper having my new design.

15 A represents the body of the paper. B is the border.

Along the bottom line of the body A appear a series of rounded arches, C C C, the caps of these arches being composed of the 20 ornamental bands a b c, laid one upon another. In front of the rounded arches are a series of pointed window-like arches, E E E E. From the top of the sides and from the vertex of these pointed arches run vertical stripes d e f, &c., over a background of zigzag lines, the stripes d f, running from the sides, being ornamented with projecting leaves. Within the pointed arches E E E are flowers D D D, resembling open water-lilies.

30 The border B has a zigzag stripe, o o, running horizontally across it, and having below it the lyre-shaped figures i i i, which appear to be set on the tops of the bands d f, &c. Fan-shaped ornaments k k k, fixed upon handles which run vertically to the lower edge of the border and appear to project from the vertical bands e g, are set in a row above the zigzag stripe o o and upon a checkered background, and in the interstices between the upper edges of the fans are rosette-shaped ornaments l l l.

I claim—

1. The design for wall-paper, consisting of the window-like arches E, substantially as described.

2. The design for wall-paper, consisting of the rounded arch-like figures C C C, substantially as shown.

3. The design for wall-paper, consisting of the flower-like figures D D, substantially as shown.

4. The design for wall-paper, consisting of the figures C D E, substantially as shown.

5. The design for wall-paper, consisting of the figures E E E and vertical bars d e f g, substantially as shown.

6. The design for wall-paper, consisting of the figures D E, substantially as shown.

7. The design for wall-paper, consisting of the figures C E d e f, substantially as shown.

8. The design for wall-paper, consisting of the figures C D E d e f, substantially as shown.

9. The design for wall-paper, consisting of the lyre-like figures i i, substantially as shown.

10. The design for wall-paper, consisting of the fan-like figures k k k, containing lance-shaped leaves radiating from a central rosette, substantially as shown.

11. The design for wall-paper, consisting of the zigzag band o and figures k k, substantially as shown.

12. The design for wall-paper, consisting of the figures i o k, substantially as shown.

13. The design for wall-paper, consisting of the figures k k k and intervening figures l l l on the background p p p, substantially as shown.

14. The design for wall-paper, consisting of the figures o p k l, substantially as shown.

15. The design for wall-paper, consisting of the group B, composed of figures i o p k l, substantially as shown.

16. The design for wall-paper, consisting of the group A, composed of figures C D E d e f, and the group B, composed of figures i o p k l, substantially as shown.

EDUARD LEISSNER.
